UNITED STATES PATENT OFFICE.

ALMON LEACH, OF UTICA, NEW YORK.

IMPROVEMENT IN COAL-OIL LAMPS.

Specification forming part of Letters Patent No. 37,349, dated January 6, 1863.

To all whom it may concern:

Be it known that I, ALMON LEACH, of Utica, in the county of Oneida and State of New York, have invented a new and Improved Lamp for Burning Coal-Oil; and I do hereby declare that the following is a full, clear, and exact description of the same, reference being had to the accompanying drawings, making a part of this specification, in which—

Figure 1 is a front view of my invention; Fig. 2, a vertical section of the same, taken in the line *x x*, Fig. 1; Fig. 3, a horizontal section of the same, taken in the line *y y*, Fig. 1.

Similar letters of reference indicate corresponding parts in the several figures.

This invention relates to an improvement in coal-oil lamps, those which are designed to be used in railroad-cars and other places where lamps are subjected to a jolting or vibratory movement.

The invention is an improvement on a lamp patented by L. J. Worden and A. Leach, the Letters Patent bearing date July 23, 1861.

The object of the present invention is to render the burner of the lamp removable, so that it may be readily detached when necessary and without changing or altering the original plan of the patented lamp above alluded to.

The invention has also for its object a more perfect form of reflector than has been hitherto used, and which will be hereinafter fully described.

To enable those skilled in the art to fully understand and construct my invention, I will proceed to describe it.

A represents the reservoir or fountain, which may be constructed in any proper manner, and which communicates with a vertical tube, *B*, by means of a tube, *C*, as shown in Fig. 2. The coal-oil, which is the burning material used, is placed in the reservoir or fountain *A*, and the tube *B* is supplied from *A* through the tube *C*.

D is a cylinder or jacket which encompasses the tube *B*, and is considerably larger in diameter than the latter. This cylinder or jacket is permanently attached to the reservoir or fountain *A*, and the tube is supported within it by one or more arms, *E*, the cylinder or jacket *D* extending some distance below the

tube *B*. In the upper end of the tube *B* there is fitted and permanently secured a socket, *F*, which is provided with an internal screw, *a*.

G represents a lamp-burner constructed in the same way as those usually employed for burning coal-oil. This burner is provided at its lower end with an external screw, *b*, which screws into the socket *F* and secures the burner to the top of the tube *B*, as shown clearly in Fig. 2.

H represents a hollow cylinder, the upper end of which is permanently attached to the burner *G* at the point where the base of the cone or deflector *I* rests on the burner. This cylinder *H* is considerably larger in diameter than the tube *B*, so as to admit of a space, *c*, of requisite width, between *B* and *H*. The latter does not extend down as low as the former, as will be seen by referring to Fig. 2. The cylinder *H* is sufficiently smaller in diameter than the jacket *D* to admit of a space, *d*, between them, which is about equal in width to the space *c* between *B* and *H*. The upper end of this space *d* is covered by an inclined perforated plate, *J*, or a piece of wire-gauze would answer the purpose. This plate *J* is permanently attached to the burner just above the top of the cylinder *H*, and to the outer edge of the plate *J* a pendent flange, *K*, is secured, said flange being of such diameter that it may when the burner is secured into the top of the tube *B*, fit snugly into the top of the jacket *D*, as shown clearly in Fig. 2.

The arrows in Fig. 2 show the manner in which the air is admitted to the flame through this burner, and the arrangement of the several parts as herein described corresponds substantially with the patented lamp of Worden and Leach, previously alluded to. In this lamp of Worden and Leach the lamp-burner is permanently attached—soldered—to the jacket *D*, tube *B*, and cylinder *H*, and the interior of the lamp is therefore not accessible unless the burner be detached by melting the solder. This feature is a very objectionable one, for the wick frequently slips down out of the wick-tube of the burner, and cannot be obtained without unsoldering the burner. By my improvement it will be seen that the burner may be detached from the lamp equally as well as the burner of an ordi-

nary lamp, and at the same time the arrangement of the parts, as shown and described in the Letters Patent of the original lamp, is preserved.

L L represent two reflectors, which are connected together by a plate, e, at their back surfaces. This plate e has a pendent slide, f, attached to it, which is fitted in a socket, g, on the upper part of the reservoir A, as shown clearly in Fig. 2. The reflectors L L are not placed in line with each other or in the same plane, but have an angular position relatively with each other, and are placed relatively with the burner or flame, as shown in Fig. 3. The reflectors are of circular form, and have convex centers h surrounded by concave rims i, as also shown in Fig. 3. The burner G is directly in front of the joint j, where the two reflectors are connected together, and the reflectors have a slightly inclined position, as shown in Fig. 2. By this arrangement it will be seen that the rays of light will be thrown both up and down and to the right and left, as indicated by the red lines in Figs. 2 and 3, the dotted red lines indicating the rays reflected by the concave surfaces i, and the solid

or unbroken lines indicating the rays reflected by the convex surfaces h.

The reflectors may be constructed of metal properly polished, or glass may be used, silvered at the back, as in the construction of mirrors.

I do not claim, broadly, a reflector having a convex and concave surface, for reflectors of that form have been previously used; but,

Having thus described my invention, what I claim as new, and desire to secure by Letters Patent, is—

1. Securing the cylinder H, perforated plate J, and flange K to the burner G, as shown, when said burner is screwed into the tube B, and all used in connection with the cylinder or jacket D, for the purpose herein set forth.

2. The combination of two reflectors, L L, formed each of concave and convex surfaces h i, connected together angularly with each other, and placed in relation with the flame of the lamp, as herein specified.

ALMON LEACH.
